UNITED STATES PATENT OFFICE.

LEWIS E. HODGES, OF TARBORO, NORTH CAROLINA.

COMMUTATOR.

1,351,648.

Specification of Letters Patent. Patented Aug. 31, 1920.

Application filed September 22, 1919. Serial No. 325,393.

To all whom it may concern:

Be it known that I, LEWIS E. HODGES, a citizen of the United States, residing at Tarboro, in the county of Edgecombe and State of North Carolina, have invented new and useful Improvements in Commutators, of which the following is a specification.

This invention relates to commutators for internal combustion engines and aims to provide a commutator which is especially designed for use upon internal combustion engines of the "Ford" type.

An object of the invention is the provision of a commutator of this character in which the entire device, including a casing and distributor arm, may be quickly and easily removed from the commutator shaft, for the purpose of cleaning or repair, and which may be easily and quickly replaced.

Another object is the provision of a commutator having novel means for preventing the escape of lubricant from the casing, the said means in addition serving to properly center the distributor arm between the walls of the casing.

Other objects and advantages of the invention will appear as the following description is read in connection with the accompanying drawings.

In the drawings:

Figure 1 is a front elevation of a commutator constructed in accordance with the present invention.

Fig. 2 is a view with the cover plate removed and partly broken away.

Fig. 3 is a central sectional view of the same.

Fig. 4 is a detail perspective view of the distributor arm and the oil aprons removed from the casing.

Referring to the drawings in detail, where-in like characters of reference denote corresponding parts, the commutator comprises a casing, which is formed of a ring or annulus 10, having a rear wall 11, which is preferably formed integral therewith, and is provided with a central opening 12, for the passage of the commutator shaft 13. The casing is provided with a ring or annulus 14, within which are embedded spaced contact plates 15. These contact plates have projecting therefrom threaded posts or stems 16, which pass through openings in the ring 14 and through an insulating sleeve 17, the latter being seated in openings 18, formed in the annular wall 10 of the casing. The

posts or stems 16 carry nuts 19, by means of which the conductor wires (not shown) are secured.

Removably mounted upon the shaft 13, is a sleeve 20, one end of this sleeve bearing against the rear wall 11 of the casing and carrying spaced aprons 21, the latter extending approximately two-thirds of the distance around the sleeve (more or less) and being adapted to bear against the inner surface of the rear wall 11 and the inner surface of the cover plate 22. This last mentioned plate may be secured to the casing through the medium of screws 23, which pass through openings in the insulated ring 14 and engage threaded openings in the rear wall 11, so that a closed casing is provided. Mounted upon a pivot pin 24, which is secured in each of the aprons 21, is a distributor arm 25, one end of the said arm being bifurcated, as indicated at 26, and having mounted therein a roller 27, which is adapted to contact with the plates 15. The roller is held in position for contact with the plates 15 by means of a spring 28, one end of which is secured to the arm 25, as indicated at 29, and the opposite end to a pin 30, carried by the aprons 21.

The sleeve 20 is secured to the shaft 13 by means of a pin 31, which passes through an opening in the said shaft and engages a notch 32, provided in the sleeve, and is held against accidental displacement by means of a cap 33, which extends over the end of the sleeve and is held in position by a nut 34. An oil port 35 is provided in the cover plate 22, said port being normally closed by a spring actuated closure 36. An auxiliary cap or cover 37 is removably positioned over the cover plate 22 and is provided with a depression or socket 38, which receives one end of a spring arm 39, the opposite end being fastened at any convenient point. The cap 37 is further provided with notches spaced around its periphery, which engage the screws 23 of the cover plate, holding the cap against radial or lateral movement, while the spring arm 39 holds the cap and cover plate in engagement. This manner of holding the cap permits of any adjustment of the commutator, which adjustment may be effected through the medium of a suitable rod or other connection with an arm 40, extending from the commutator.

The invention is susceptible of various changes in its form, proportions and minor details of construction and the right is herein

reserved to make such changes as properly fall within the scope of the appended claims.

Having described the invention, what is claimed is:

- 5 1. In a commutator, a rotatably mounted shaft, a casing surrounding the shaft, said casing including front and rear walls having openings for the passage of the shaft, a distributor arm rotatable with the shaft
10 for engagement with spaced contacts carried by the casing and combined means located within the casing for preventing the escape of lubricant through the openings in the front and rear walls of the casing and
15 to provide a mounting for the distributor arm:
  - 20 2. In a commutator, a rotatably mounted shaft, a casing surrounding the shaft, said casing including front and rear walls having openings for the passage of the shaft, a distributor arm rotatable with the shaft for engagement with spaced contacts carried by the casing and spaced aprons carried by the shaft and operating upon the
25 inner surfaces of the front and rear walls of the casing.
  3. In a commutator, a rotatably mounted shaft, a casing surrounding the shaft, said casing including a rear wall and a removable front wall, both having openings therein for the passage of the shaft, a sleeve surrounding the shaft within the casing and having one end surrounding the opening in the rear wall and its opposite end extend-

ing through the opening in the front wall, 35 a distributor arm rotatable with said sleeve for engagement with spaced contacts carried by the casing and means engageable with the sleeve and shaft and contacting with the outer wall to hold the parts assembled, 40 an auxiliary cover plate and means for removably holding the plate in position in a manner to permit of the rotation of the casing.

4. In a commutator, a rotatably mounted 45 shaft, a casing surrounding the shaft, said casing including a rear wall and a removable front wall having openings therein for the passage of the shaft, a sleeve surrounding the shaft within the casing and having 50 one end surrounding the opening in the rear wall and its opposite end extending through the opening in the front wall, a distributor arm rotatable with said sleeve for engagement with spaced contacts carried by the 55 casing, means engageable with the sleeve and shaft and contacting with the outer wall to hold the parts assembled, spaced aprons carried by the sleeve for contact with the inner surfaces of the front and rear walls to properly position the distributor arm between said walls and to prevent the escape of lubricant, an auxiliary cover plate and means for removably holding the latter in position in a manner to permit of rotation of the 60 casing.

In testimony whereof I affix my signature.
LEWIS E. HODGES.
